1,939,759

GAME

Pickens P. Awalt, San Francisco, Calif.

Application July 21, 1931. Serial No. 552,229

6 Claims. (Cl. 273—139)

An object of my invention is to provide a game which requires the skill of the operator in obtaining a large number of points during the first part of the game. These points entitle the player to remove a like number of concealed numbers printed on folded paper, and these numbers in turn, if ending in a predetermined figure, will give the player the number of points which count in the final standing. The player receiving the highest number of final points is the winner of the game.

The device has novel mechanism for locking up different parts so as to prevent unauthorized tampering with the device. The owner of the game has a drawer with a number of compartments for receiving the coins, these compartments corresponding with the receptacles that temporarily hold the coins. By this arrangement the operator can check on the various numbers of points received by the players over a given playing period, such as a day.

A further object of my invention is to provide a device of the type described which is simple in construction, and which is durable and efficient for the purpose intended. The device is attractive and contains novel illuminating means.

Other objects and advantages will appear in the following specification, and the novel features of the device will be particularly pointed out in the appended claims.

My invention is illustrated in the accompanying drawings forming a part of this application, in which

Figure 1 is a front elevation of the device; Figure 2 is a section along the line 2—2 of Figure 1;

Figure 3 is a sectional view along the line 3—3 of Figure 1;

Figure 4 is a section along the line 4—4 of Figure 6;

Figure 5 is a section along the line 5—5 of Figure 1;

Figure 6 is a section along the line 6—6 of Figure 4;

Figure 7 is a sectional view through a part of the device;

Figure 8 is a perspective view of a part of the device;

Figure 9 shows a ticket used in the device;

Figure 10 is a section along the line 10—10 of Figure 11;

Figure 11 is a section along the line 11—11 of Figure 10; and

Figure 12 is a section along the line 12—12 of Figure 11.

In carrying out my invention I provide a casing indicated generally at 1, see Figures 1 and 2, this casing having a base 2, a drawer containing compartment 3, a mechanism receiving compartment 4, and a cover 5 for the compartment 4, this cover being hinged at 6 and being locked in place by a locking means 7. The side walls 8 of the compartment 4, see Figure 5, are provided with grooves 9 and 10 for receiving a front sliding panel 11, and a rear sliding panel 12, see Figure 2. The panels 11 and 12 are connected to each other by cords 13 passing over idler pulleys 14 and having their ends connected to the panels. The weight of the two panels is such that they will remain in the position into which they are manually moved. The raising of either panel will cause the other to lower.

When the game is ready for playing the panels 11 and 12 are raised in the position shown in Figure 2, and when the game is locked so as to prevent further playing, the front panel 11 is moved down between a protecting glass 15, see Figure 4, and a rear glass 16, see Figure 2. The panel 12 when in raised position, see Figure 4, extends from the underside of the cover 5, to a position slightly below a protecting glass 17. A lock 18 may be used to prevent the panel 12 from being manually moved downwardly.

It is best to describe the game step by step as it is played, and to set forth the structure in the same order. In Figure 1, I show a coin or token receiving chute 19 disposed on the side 90 of the device and above a gun 20. The gun extends into the compartment 4 and into the selecting device 29, and is pivoted at 21'. The construction of the gun is shown in Figures 10, 11 and 12, and it comprises a casing 21, a coin guide 22 and a back 23. A rod 24 extends from the back 23 through the end 25 of the casing 21, and is provided with a handle 26. Figure 10 shows springs 27 yieldingly holding the coin guide or ejector in the position shown. The coin chute 19 delivers the coin to the slot 28 in the casing 21, and the coin passes through the slot and into the coin guide and ejector 22. The player now retracts the coin ejector 22 by means of the handle 26, and then quickly releases the handle. This causes the coin to be propelled from the gun and into a coin selecting device indicated generally at 29, see Figures 1 and 2. The gun can be swung about the pivot 21' so as 110

to permit the player to aim the gun in the direction desired.

The coin selecting device includes a back piece 30 provided with pegs 31 arranged in a predetermined manner. The coins drop between the back piece 30 and the glass 32. At the bottom of the coin selector 29, I provide a plurality of partitions 33 which form coin receiving compartments 34, see Figures 1 and 5, and the bottoms of these compartments are temporarily closed by a trap door 35. The compartments are provided with numbers 36 reading "20—0—4—0—3—0—5—0".

It will be noted that the compartment 34 numbered "20" is positioned beneath a striker plate 37, see Figure 1, which is mounted upon screws 38 and is held in position by means of springs 39. Figure 3 shows the striker plate 37 as having a slot 40 large enough to receive a coin. If the aim of the player is accurate, a coin can be shot from the gun and will pass through the slot 40 and drop into the compartment 34, numbered "20". As many coins as desired may be fired from the gun, and these will be temporarily retained in the compartments 34.

When the player is finished, the operator releases the coins from the compartment 34 and drops them into a coin receptacle 41. The receptacle 41, see Figure 6, has partitions 42 which divide the receptacle into compartments 45 corresponding with the compartments 34. Spring actuated trap doors 43 close the openings 44 leading into the compartments 45.

The operator actuates the trap door 35 by depressing a handle 46, see Figure 4. The handle 35 is connected to an arm 47 by means of a rod 48, and Figure 8 shows the arm 47 as having a slot 49 for receiving a crank portion 50 of a rod 51 that carries the trap door 35. When the operator releases the handle 46 a spring 52 returns the trap door to closed position. The coins drop from the trap door 35 down upon the trap doors 43, and into the compartments 45.

Before the coins have been freed from the trap door 35 the operator counts the number of coins in the compartments 34 and multiplies the number of coins in each compartment by the number of the compartment. For example, if the player has shot one coin into the compartment 34, numbered "20", three coins into the compartment numbered "4" and five coins into compartment numbered "0", he will have a total of twenty times one, plus three times four, equalling thirty-two points. The player will, therefore, have thirty-two tries at the punch board 11. A wire plunger 53 is used for the punch board 11, and ejects strips of paper 54, see Figure 9, and drops them between the glasses 16 and 32, and down upon a trap door 55, see Figure 2. After the thirty-two pieces of paper have been deposited upon the trap door 55, the operator depresses a handle 56 which moves a rod 57 downwardly, and Figure 8 shows how this rod swings a lever 58 about its pivot 59. The lever has a slot 60 that slidably receives a crank 61 of a rod 62 that supports the trap door 55. The folded strips of paper drop from the trap door 55 into a cup 63 where they may be removed by the player. The strips carry numbers from 0 to 10,000 or more, and if the last figure in these numbers corresponds with the number of the compartments 34 in which the player has projected the coins, the player will receive final points equaling the sums of these numbers. The next player will play in like manner to the one

already described, and his points may be more or less than the first player irrespective of whether the total points received from the compartments 34 is greater or less than the first player's points.

As an example, the player A shoots a check slug or token 64, see Figure 6, by means of the gun 20 into a compartment 34 designated by a number 36, which he has chosen, say number 5, and if he wins he then punches five sealed, numbered tickets 54 and if three of these tickets end in the number 5, his final total number of points will be 15. Player B then tries to play into the number 20 compartment, and if successful punches 20 tickets numbered 54, and if none of these tickets end in the number 20 he makes no final points. In like manner the other players will follow, and the winner is the one receiving the greatest number of final points.

The device is illuminated indirectly by lights 65 and 66, reflectors 67 being placed in back of the lights 66. An overhead light 67' with its reflector 68 is also used, see Figure 2.

I have already described how the punch board 11 can be moved into a protected position when the game is not used, and how the panel 12, 100 cooperating with the glass 17, will close the back of the device. A glass 69 is positioned in back of the punch board 11, and prevents access to the device 29 when the punch board is moved between the glasses 15 and 16. The operator can 105 also lock the handles 46 and 56 against movement, and this is accomplished by a hinged member 70, see Figure 7. This member is swingable from the position shown in Figure 2 into that shown in Figure 7. If desired a lock 71 may 110 be used for securing the member 70 in raised position.

The game can be used for advertising purposes: for example, a merchant may give a prize to the customer who makes the highest score for 115 the day or week, etc., the merchant requiring the customer to make a purchase for each play. The game requires skillful playing and affords a source of amusement.

While I have shown only the preferred form 120 of my invention, it should be understood that various changes and modifications may be made within the scope of the claims hereto attached, without departing from the spirit of the invention.

I claim:

1. A game comprising a punch board receiving compartment having transparent front and back walls, a punch board movable from between the walls to a position thereabove, a chute disposed in back of the compartment for receiving tokens from the board, a false bottom closing the bottom of the chute for temporarily holding the tokens where they can be viewed through the transparent walls, a receptacle extending from the chute to a position in front of the compartment, and means for moving the false bottom for dropping the tokens into the receptacle.

2. A game comprising a punch board receiving compartment having transparent front and back walls, a punch board movable from between the walls to a position thereabove, a chute disposed in back of the compartment for receiving tokens from the board, a false bottom closing the bottom of the chute for temporarily holding the tokens where they can be viewed through the transparent walls, a receptacle below the false bottom and means for moving the false bottom for dropping the tokens into the receptacle.

3. A game comprising means for mounting a punch board in upright position, a chute disposed in back and below the punch board for receiving tokens from the board, a transparent front wall for the chute, a false bottom closing the bottom of the chute for temporarily holding the tokens where they can be viewed through the transparent wall, a receptacle extending from the chute to a position in front of the transparent wall and means for moving the false bottom for dropping the tokens into the receptacle. 5. A game comprising a punch board receiving compartment having transparent front and back walls and a punch board movable from between the walls to a position thereabove whereby tokens punched from the board in its elevated position may be viewed through the transparent walls when dropping downwardly, and manually controlled means for arresting the tokens in their downward travel. 80
10. A game comprising a punch board receiving compartment having transparent front and back walls and a punch board movable from between the walls to a position thereabove whereby tokens punched from the board in its elevated position may be viewed through the transparent walls when dropping downwardly. 15. A game comprising a punch board receiving compartment having transparent front and back walls and a punch board movable from between the walls to a position thereabove whereby tokens punched from the board in its elevated position may be viewed through the transparent walls when dropping downwardly. 20

6. A game comprising a transparent wall, a punch board and means for slidably mounting the punch board with freedom of movement from an inactive position behind the wall to an active position above the wall whereby the board is protected when in inactive position, and whereby tokens punched from the board in active position may be viewed through the transparent wall while dropping. 85
